STENCIL CONTROLLED PRINTING MACHINE

Albert W. Mills and Louis J. Herman, Endicott,
N. Y., assignors to International Business Ma-
chines Corporation, New York, N. Y., a corpo-
ration of New York

Application April 12, 1946, Serial No. 661,692

6 Claims. (Cl. 101—48)

1

This invention relates to printing machines of the kind in which impressions are made from stencil or embossed address printing plates sequentially fed through the machine and wherein impressions are made directly from such plates on record material such as envelopes, or the like, and this invention pertains particularly to improvements which insure certainty of a printing relationship between the printing plates and envelopes before a printing impression can be effected upon an envelope.

The particular value of the present machine resides in the capability of enabling addresses to be printed upon envelopes from printing plates previously utilized for printing addresses upon checks to be mailed in the envelopes.

In a broad aspect the main object of this invention is to provide a printing mechanism for printing from stencil printing plates, or the like, with a control means therefor which prevents its operation to print upon an envelope from a stencil printing plate unless both an envelope and stencil plate have been fed clear to a printing position. Several reasons may be advanced for failure to move either a stencil or envelope to printing position but is due principally to the exhaustion of a supply of envelopes or stencil plates, or failure to properly feed an envelope or stencil plate out of the envelope or stencil plate supply hoppers clear to printing position. These operations are necessary for proper printing operations and herein the continuity of printing operations is made dependent upon all of these conditions being fulfilled.

Another object of the invention is to provide the machine with separately controlled clutches, one for the picker which feeds an envelope out of the envelope hopper, and another for the picker which feeds the stencil out of the stencil hopper, and to provide control means which prevents the operation of either of such clutches whenever the envelope or stencil hopper becomes empty, which generally happens after the machine has been running and to also prevent a subsequent engagement of both clutches upon failure to feed a stencil or envelope out of the related supply hopper toward printing position.

Another object of the invention is to provide the machine with a separately controlled clutch for effecting a printing impression upon the envelope directly from a stencil and to prevent the engagement of this clutch unless an envelope is in correct position to be printed, and to also prevent the engagement of this clutch when stencils and envelopes fail to feed out of the related supply hopper to printing position.

2

Another object of the invention is to provide the envelope and stencil feeding mechanism with feeding rollers which function to convey the printed envelope and associated stencil to a discharge position and concomitantly a following envelope or stencil from the supply hoppers toward printing position, and in fulfilling the object of this invention provision is made to prevent engagement of a clutch which drives such feeding rollers upon exhaustion of the supply of stencils or envelopes, or upon failure to feed a stencil or envelope from the supply hoppers towards printing position.

A still further object of the invention is to provide the stencil feeding mechanism with a shuttle or supplemental stencil feeding device which shifts a stencil to the set of discharge rollers which feed the stencil already employed for printing to discharge position, and similarly, the engagement of the clutch which operates such shuttle is not effected unless the aforementioned conditions in the machine ensue.

Another object of the invention is to provide an address printing machine functioning in two cycles of machine operation, one of which cycles is utilized to feed a stencil and envelope to printing position and the other cycle is utilized to effect an address printing operation from said stencil on an underlying envelope and to provide control means effective to cause such cyclic operations in the mentioned sequence, and with a continuity which depends upon the preceding conditions in the machine being fulfilled.

From the preceding it is obvious that machine operations are so interlocked and made so dependent upon the presence of a supply of cards and envelopes and their proper passage and position in the machine that the proper performance of the machine, namely, address printing operations on the envelopes are inhibited unless the desired conditions are fulfilled. Hence, failure to feed a stencil through the machine without an accompanying printed envelope is prevented, thus insuring a printed envelope for each stencil which is the principal object and result to be secured by envelope address printing machines.

It should be noted that the use of stencils in the form of cards as printing instrumentalities is merely illustrative and metal embossed printing plates or other kinds of plates or stencils can also be used. Furthermore, printing need not be effected solely upon envelopes, since other record materials, such as checks, other cards, etc. can receive the printing from the printing plates.

Other objects of the invention will be pointed out in the following description and claims and illustrated in the accompanying drawings, which disclose, by way of example, the principle of the invention and the best mode, which has been contemplated, of applying that principle.

In said drawings:

Fig. 1 is a vertical sectional view of the machine.

Figs. 2 and 2a when joined together with Fig. 2 on the top show a horizontal sectional view of the machine.

Fig. 3 is a sectional view taken on the line 3-3 of Fig. 2 and illustrates the detail of a gear drive embodied in the machine.

Fig. 4 is a sectional view taken on the irregular section line 4-4 of Fig. 2.

Fig. 5 is a plan view taken on the line 5-5, of Fig. 2 showing the clutch control drive for certain parts of the printing mechanism.

Fig. 6 is a plan view taken on the line 6-6 of Fig. 2.

Fig. 7 is a view in side elevation showing the detail of the electromagnetically controlled picker clutch for feeding envelopes.

Fig. 8 is a view in side elevation showing the details of the electromagnetically controlled clutch for feeding the stencils.

Fig. 9 is a view in side elevation showing the detail of the electromagnetically controlled clutch for operating the shuttle.

Fig. 10 is a wiring diagram of the machine.

Fig. 11 is a timing diagram showing the events that occur in the four successive cycles of the machine after starting the operation of the machine, in which a feed roll cycle and a following print cycle are utilized for a complete functioning of the machine.

Stencils and envelopes

The selected embodiment of the invention shown in the drawings is adapted for the printing of addresses on conventional envelopes from suitable printing plates, such as card stencils, so that such addressed envelopes can be used to mail checks or other business instruments. When card checks are addressed by the same series of printing plates it is obvious that there should be a printed envelope for each check. Printing plates of the card stencil type are well known and herein they may comprise the type shown in the patent to A. W. Mills et al., No. 2,357,487, dated September 5, 1944. In general, each consists of a card of the type used in card controlled accounting machines but having a window covered by stencil tissue material. The stencil tissue is cut by a typewriter to record the name and address by the arrangement shown in the patent just mentioned. Prior to use in the present machine the stencil cards are preferably "charged" or conditioned by the machine shown in Patent No. 2,357,486 to A. W. Mills et al., dated September 5, 1944. The conditioned stencils are placed in the supply hopper of the present machine and re-inking herein enables the imprints to be clearly made on the envelopes. The envelopes are of a conventional type in that they are provided with gummed flaps underneath which a picker projects for feeding the envelope from the supply hopper.

Main driving mechanism

Mounted in the base of the machine is a motor 9 (Fig. 2a) which continually rotates a pulley 10 which has a belt connection 11 to a pulley 12

secured to the drive shaft of a speed reduction drive unit 13 (Fig. 1). The driven shaft 14 of the speed reduction drive unit is thus rotated at a desired speed and continually as long as the motor 9 is in operation. The shaft 14 extends from the front of the machine to the back and the front extension carries a series of continually running cams which close contacts involved in the electrical circuits at predetermined times in the machine operation. The speed reduction unit 13 is supported by a sub-base 16 of the machine. A bracket is also attached to the sub-base 16 so that the rearward extension of shaft 14 can be journaled by the bracket arms 15. To the shaft 14 there is secured a bevel gear 17 meshing with a bevel gear 18 secured to a short drive shaft 19 which extends horizontally of the machine, that is, from the left to the right. Shaft 19 is journaled in a bracket 20 (Fig. 2a) also carried by the sub-base 16 of the machine. Between the bracket arms 15 there is attached to the main drive shaft 14 a cam 62 which operates the stencil card picker mechanism and a cam 81 which operates the stencil card shuttle. The function of these cams will be described in subsequent sections of the description of the operation of the machine.

Envelope feed and clutch

30 The envelopes are placed in a supply hopper 21 (Fig. 1) with the flaps down and at the rear of the hopper, i. e. the edge of the envelope having the flap is the leading edge. The envelopes are fed from the front of the machine to the rear singly from the hopper by a picker mechanism now to be described. At the same time the envelope feed rolls are rotating to receive and feed the envelope fed from the hopper and move it to printing position.

40 Pivoted to a rock shaft 22 (Figs. 2a and 7) is a pair of upstanding arms 23, each of which carries a related spring steel picker knife blade 24 which slides over a guide plate 25 to get between the flap and the back of the envelope in order to move the envelope through a card throat comprising a roll 25a of impregnated cork to the first set of feed rolls 170 which carry it to printing position. A spring 23c returns the arms 23 and an adjusting screw 23b is used for setting the positions of the picker blade 24 in relation to the envelope flap. To one of the arms 23 there is pivoted by an eccentric screw 27a a link plate 27 having a bayonet type slot comprising a horizontal slot 28 and a vertical slot 29. A follower arm 30 fixed to a rod 31 carries a pin 32 cooperating with said bayonet slot. The follower arm 30 carries a roller 33 cooperating with a profile cam 34 secured to the continually rotating drive shaft 19. A spring 35 extends between the end of link plate 27 and the follower arm 30 and tends to move the free end of the link plate 27 downwardly normally, i. e. in the absence of the energization of clutch magnet 36 a hook 37 integral with the link plate 27 will strike and rest upon the armature 38 of the clutch magnet 36. The eccentric screw 27a adjusts the position of hook 37 with relation to the armature 38. To the link plate 27 there is secured a bracket plate 39 having an extension 40 in the path of a stud 41 attached to cam 34. In the absence of the energization of the clutch magnet 36 the movement of stud 41 concentrically away from the extension 40 will enable spring 35 to rock the free end of link plate 27 downwardly until hook 37 strikes the top of the armature 38. This will hold link plate 27 in

such a position that the oscillation of arm 38 under control of cam 34 will cause stud 32 to reciprocate idly in horizontal slot 28 without effecting any movement of the picker through the inter-linkage. When magnet 36 is energized its armature will be attracted to a position where it is out of the path of hook 37 and movement of the free end of link plate 27 downwardly in the manner just explained will cause the vertical slot 29 to be received by the stud 32. Hence, a clutch connection is established between follower arm 38 and the linkage extending to the picker. Oscillation of the follower arm will, accordingly reciprocate the picker to feed the lowermost envelope. The stud 41 normally maintains hook 37 out of contact with the armature 38 to eliminate pressure between such parts so that the armature 38 can be freely attracted by energization of clutch magnet 36 when this relationship is effected.

The stud 41 also acts on the extension 40 at the end of the envelope feed operation to elevate link plate 27 upwardly so that hook 37 is again disposed over the end of armature 38, which, in the meantime, has been returned to latching position by a spring 42.

Stencil card feed clutch

Referring to Figs. 2 and 8 the stencil cards 44 are disposed in a stencil card supply hopper 45 and the trailing edge of the lowermost stencil is engaged by a picker 46 which has a swivel connection 47 to a slidably mounted plate 48. The latter has a fork connection 49 with an arm 50 secured to a rock shaft 51. To an arm 52 secured to rock shaft 51 there is pivoted a depending link 53. To the free lower end of the link 53 there is connected a spring 54 which is extended in such manner as to tend to draw the lower free end of the link 53 to the right when the link is unlocked for this movement by an arm 69 but this action is normally frustrated by the abutment of a lug 54a with the extremity of an armature 55 of a stencil card feed clutch control magnet 56. When the magnet 56 is energized the armature 55 is attracted upwardly, moving the armature out of the path of lug 54a. Spring 54 shifts the free end of the link to the right when the link is unlocked by arm 69 so that a horizontal slot 57 in the link cooperates with a stud 58 of a follower arm 59. The follower arm 59 is loose on a rod 60 and its roller 61 cooperates with a cam 62 secured to the drive shaft 14. Energization of the clutch magnet 56 enables a clutch connection between the follower arm 59 and link 53 to cause the reciprocation of the link 53 and through arms 52, 50 the picker 46 is reciprocated to feed the leading edge of the stencil card to a throat to be subsequently described.

In the absence of the energization of magnet 56 the follower arm 59 reciprocates idly without effecting any movement of link 53, and in such idle operations, which occur during each print cycle, the stud 58 moves idly in a long vertical slot 63 of the link 53. A spring 64 attached to the link 53 aids in its restoration and the return movement of the picker 46.

Pivoted on the rod 60 is a triple armed member having an arm 65 cooperating with a roller 66 carried by the cam 62; an arm 67 to which a spring 68 is connected, and an arm 69 bearing against a cam edge 70 of link 53. In the normal position of triple arm 65, 67, 69, link 53 is held over to the left to enable a little clearance between the lug 54a and the cooperating end of the armature 55, thus eliminating any contact or

pressure between these parts and enabling the free attraction of the armature. As the roller 66 moves concentrically away from the arm 65, spring 68 rocks the arm 69 upwardly so that if the armature 55 is now attracted by the energized magnet 56, spring 54 can now shift the lower end of link 53 to the right to effect the clutch connection. As link 53 is lowered the arm 69 will be above it. When link 53 is fully restored, roller 66 will now engage arm 65, rocking arm 69 downwardly to cam link 53 to the left to the normal position shown in Fig. 8 where it is relatched by the armature 55.

The leading edge of the stencil card being fed passes between a card throat comprising a blade 71 and a roller 72 which are separated a distance to restrict feeding of stencils to one only. The reciprocation of the picker knife feeds the stencil card from left to right, over a plate 73 to the first set of feed rolls 75L (Fig. 2) which rotate to feed the card to the extreme right. When feed rolls 75L stop in their rotation they hold the stencil in printing position above the envelope which in the meantime has been fed from front to back in the same feed roll cycle and over a plate 74. This is effected because the envelope feed rolls and stencil card feed rolls feed both to printing position at the same time since they are clutched to the operating means 30 by the same clutch to be later described.

Stencil card shuttle and clutch

The spacing of the feed rolls 75L, 75R of the stencil card feed is greater than the dimension 35 of the stencil card in its direction of feed (see Fig. 2) and only the first set of feed rolls 75L holds the stencil card at printing position. An intermediate card movement is provided to move the stencil card from the first set of feed rolls 75L to the second set 75R or discharge rolls. This movement is obtained by means of a card 40 shuttle which seizes the trailing edge of the stencil card already used for printing and at printing position and shifts the stencil card from the printing position to the discharge rolls 75R. The card shuttle operation is under control of a clutch magnet 80 (Fig. 9) which is de-energized after the envelope printing operation to effect the shuttle movement.

50 This clutch is best shown in Figs. 2, 2a and 9 and is a back acting interposer type clutch, i. e. the shuttle operates when the clutch magnet 80 is deenergized and is declutched as long as the clutch magnet 80 is energized.

55 Secured to the drive shaft 14 is a cam 81 co-operating with the roller 82 of a follower arm 83 which is connected by a screw stud 84 to a link 85. The continually rotating cam 81 continually reciprocates the link 85 which is guided in brackets 86 for such movement. A spring 87 attached to the free end of the link retracts the link 85 and maintains the follower roller 82 against the cam 81. Pivoted on a stud 88 carried by an arm 89 is a clutch dog 90. Spring 91 normally tends to effect a clutch engagement between a lug 92 of the clutch dog 90 and a notch 93 in said link, but is restrained from so doing by the armature 94 of the clutch magnet 80 which abuts an extension 95 of the clutch dog 90 as long as the magnet 80 is energized. When the magnet 80 is deenergized a spring 96 attached to armature 94 moves the armature out of cooperative relationship with the extension 95, and spring 91 is now free to rock the clutch dog 90 so that lug 92 engages the notch 93 to

thereby effect the clutch connection between arm 89 and link 85. Before a shuttle operation is completed the magnet 80 is reenergized to attract armature 96. This places its end in the path of the extension 95 and as the link 85 returns to the right, the extension 95 is struck by the armature 94 to rock the clutch dog 90 to an unlatching position.

The link 85 is reciprocated during each cycle but the clutch connection is only made for the feed roll cycles. In other cycles, or each print cycle, the clutch magnet 80 remains deenergized and the armature 94 holds the clutch dog 90 to prevent the engagement of lug 92 with the clutch notch 93.

The arm 89 is secured to a rock shaft 97 and to this shaft 97 there is fastened an arm 98 which has a link connection 99 to the shuttle plate 100.

Referring to Figs. 1, 2 and 9 the shuttle plate 100 carries rollers 101 rolling in a guide track formed in a frame bar 102 (see Fig. 1). Referring to Figs. 2 and 9, pivoted on a stud 103 is a spring urged claw shaped member 104 which is shaped at its extremity to engage the trailing edge of a card when it is held by the first set of feed rolls 75L. As a result of the clutch connection, member 104 moves to the right as viewed in Figs. 2 and 9 as the two sets of card feed rolls are rotating and thus shifts the stencil card to the right to be seized and fed by the now rotating discharge feed rolls 75R. As the member 104 returns to the left it arrives at a position to engage the trailing edge of the next stencil card fed out of the hopper by the card picker.

Stencil card feed rolls and feed roll clutch

These comprise the two sets 75L, 75R, the set 75L receiving the leading edge of the stencil card which is fed by the stencil card picker mechanism and the set 75R subsequently receiving the leading edge of the same. These sets of rollers are separated by suitable mountings a distance apart greater than the width of the stencil card in a card feed direction, resulting in the condition that the foremost set of feed rollers 75L holds the stencil card at printing position but the leading edge of this card is not received by the discharge set of rollers 75R. As was previously described, the shuttle engages the trailing edge of the stencil card from which printing has been effected and feeds it to the discharge rollers 75R which are rotating so that the latter discharges the stencil card to a suitable receiving hopper. Discharge rollers 75R rotate faster than rollers 75L to avoid interference between incoming and outgoing stencils. The selective clutch drive for these feed rollers will now be explained:

Referring to Fig. 1, to the rearward extremity of shaft 14 there is secured a bevel gear 110 meshing with a bevel gear 111 secured to a main vertical drive shaft 112, which shaft is mounted in the back of the machine by suitable brackets. To shaft 112 there is secured a gear 113 (Fig. 6) meshing with an idler gear 117 which meshes with a gear 118 attached to a short vertical drive shaft 119. To shaft 119 there is secured a clutch disk 120 (Fig. 6) having a clutch notch which is engaged by a tooth of a clutch dog 121. The clutch dog is held out of engagement with clutch disk 120 by a clutch arm 122 which is operated when a clutch magnet 123 (Fig. 10) is energized. The clutch dog is carried by an arm 124 secured to a sleeve 125. The above is a general descrip-

tion of a well known form of clutch. By circuits to be subsequently described in detail the magnet 123 is energized so that drive shaft 112 is clutched to the sleeve 125 which is supported by the drive shaft 119 mounted in bearings in suitable brackets. To the sleeve 125 there is secured a bevel gear 126 meshing with a bevel gear 127 secured to a drive shaft 128 (see Figs. 3 and 6).

Bevel gear 130 which is secured to the drive shaft 128 meshes with a bevel gear 133 attached to a shaft 132. A gear 134 attached to shaft 132 meshes with a gear 135 rotatably mounted on a short stub shaft. Gears 136 and 137 are integral with gear 135 and from gear 137 there is a gear drive to the upper and lower stencil feed roll shafts 145, 152 (Fig. 2) associated with the first set of feeding rollers 75L. Gear 137 meshes with a gear 138 secured to a shaft 139 and attached to shaft 139 is a bevel gear 140 meshing with a bevel gear 141 secured to a drive shaft 142. Attached to shaft 142 is a gear 143 (Fig. 2) meshing with a gear 144 secured to a feed roll shaft 145 which carries the upper feed rollers of the set 75L.

Gear 137 also meshes with a gear 146 (Fig. 3) secured to a shaft 147 and a bevel gear attached to shaft 147 meshes with a bevel gear 148 (Fig. 3) secured to shaft 149. A gear 150 (Fig. 2) attached to shaft 149 meshes with a gear 151 secured to feed roll shaft 152 (Fig. 2) to which is secured the lower feed rolls of the set 75L.

As best shown in Fig. 6, shaft 139 extends to the right to drive the upper feed roller shaft 160 (Fig. 2) of the discharge set 75R by the following gear drive connections. To the shaft 139 there is secured a bevel gear 155 (Fig. 6) meshing with a bevel gear 156 secured to shaft 157. Attached to shaft 157 is a gear 158 (Fig. 2) meshing with a gear 159 secured to the upper feed roll drive shaft 160 to which is secured the upper feed rolls of the discharge set 75R.

Shaft 147 also extends to the right (Fig. 6) and has secured to it a bevel gear 161 meshing with a bevel gear 162 secured to a shaft 163. To the shaft 163 there is secured a gear 164 (Fig. 2) meshing with a gear 165 secured to the lower feed roll drive shaft 166 to which is secured the lower feed rolls of the discharge set 75R. The shafts carrying the feed rolls 75R and 75L carry suitable disks to hold the feed rolls spaced apart, since the disks are in contact with each other. These hold the rolls spaced apart to less than the thickness of the stencil card.

Envelope feed rolls

These comprise two sets 170 and 171 (Fig. 1), the set 170 receiving the leading edge of the envelope which is fed by the envelope picker mechanism and the concomitant rotation of such feed rolls receives an envelope to feed the envelope to printing position and hold the envelope when the rotation of such feed rolls terminates. These rolls may be spaced apart similar to that described above for the stencil card feed rolls. The driving connections for such rolls come from the clutch shown in Fig. 6 which causes the rotation of the driven shaft 128 (Fig. 6) so that the stencil card feed rolls and envelope feed rolls are driven in synchronism. The feed rolls for the envelope are, of course, at right angles to the stencil card feed rolls so that the envelope is fed transversely with respect to the stencil card.

The upper and lower front envelope feed rolls 170 are driven by gear connections from shaft 128. Shaft 132 (Figs. 3 and 6), which it will be recalled is driven by shaft 128, comprises the

lower feed roll shaft for the lower feed rolls of the front set 170 and, therefore, drives such feed rolls. Gear 136 (Figs. 3 and 6) meshes with a gear 172 secured to the upper feed roll shaft 173 to drive the upper feed rolls of the set 170.

The rearward set of feed rolls 171 discharges the envelope from which printing has been effected to the envelope storage hopper. The feed rolls 171 preferably rotate faster than the set 170 to avoid interference between envelopes feeding in and those feeding out, or being discharged. To the shaft 128 there is secured a bevel gear 174 (Fig. 6) meshing with a bevel gear 175 attached to the lower feed roll shaft 176 of the discharge set of lower feed rolls 171. The upper feed roll drive shaft of the discharge set 171 need not be driven but by a friction drive with the lower feed rolls they will be rotated to feed the printed envelope to the discharge hopper. Through the described drive connection both sets of envelope feed rolls 170 and 171 are concomitantly driven to feed a new imprinted envelope to printing position and to discharge an envelope from which printing has been effected to discharge position.

Stencil printing mechanism

To effect the operation of the stencil printing mechanism during printing cycles, a magnetically controlled clutch is employed, this being shown in Fig. 5. The clutch construction is similar to that previously described and is identical to the form of clutch shown in Fig. 21 of British Patent No. 523,709.

The main drive shaft 112 extends upwardly to nearly the top of the machine and has attached thereto a clutch disk 178 (Fig. 5) having a clutch notch engageable by the clutch tooth 179 of a clutch dog 180. The clutch dog 180 is pivotally mounted on an arm 181 secured to a sleeve 182. The normal position of the clutch dog which prevents its engagement with the clutch disk 178 is maintained by a clutch control arm 183. It is sufficient to state that by an intermediate mechanism energization of the print control clutch magnet 187 causes the rocking of arm 183 to disengage it from the clutch dog 180, whereupon the latter effects a clutch connection to the clutch disk 178 to cause the rotation of the sleeve 182 a complete revolution.

Secured to the sleeve 182 is a bevel gear 184 (see Fig. 1) meshing with a bevel gear 185. Bevel gear 185 is attached to a shaft 186 (see Fig. 5) from which shaft driving connections are made, as will be subsequently described, to parts of the stencil printing mechanism which are to be operated.

The printing unit consists of a series of ink transfer rollers, an inking printing impression roller and an ink reservoir. The printing mechanism is fabricated as a single unit which may be attached to and removed from the machine. This mechanism is primarily supported by two side plates 190 and 191 (Fig. 2) which are spaced apart and connected by a front top cross plate 192 (Fig. 1), a back top cross plate 193, a front bottom cross plate 194 as well as other transverse members to be subsequently described. The side plates 190, 191 rest upon the cross bars 195, 196 supported by the main side frames 197, 198 of the machine. In such position the unit is fixed in its proper relation with respect to the rest of the machine. The entire printing unit may be withdrawn from the machine for the purpose of assembly, inspection, etc.

The printing unit includes an inking printing

roller 200 and four ink distributing rollers 201, 202, 203, and 204, of which rollers 200, 201, 202, 203 are rotatably mounted in the frame plates 190 and 191 while the roller 204 is mounted in a removable ink supply unit.

The impression inking roller 200 cooperates with a stencil card 44 in printing position (see Fig. 6) to press ink through the cutout window portion 44a of the stencil forming the letters 10 and 15 and is mounted on a shaft 205, encircled by bushings 206 (Fig. 1) the extremities of which are flattened to ride in vertical slots 207 in plates 190 and 191, respectively. The right end of shaft 205 is provided with a ratchet wheel 208 (Fig. 4) 20 with which cooperates a dog 209 having a tooth 208 and actuated upwardly by a spring 210. The dog 209 is provided with a wide lug 211 (Fig. 2) 25 to which the spring 210 is attached and which lug bears against an edge of the side frame 191 when the printing roller 200 is in its uppermost or retracted position.

The printing roller 200 is moved downwardly 25 into contact with the stencil portion of a stencil card by means of cams 212 (Figs. 2, 4, 5) which are secured to a drive shaft 213 rotatably mounted in the side plates 190 and 191. Ball bearings 214 (Fig. 2) on the shaft 205 have their outer ball races in the plane of cams 212 so that the ball 30 races act as cam follower rollers for the cams 212. It is evident that when the shaft 213 is rotated one revolution the roller 200 will be depressed into contact with a stencil. As shown in Fig. 5 shaft 186 has secured to it a bevel gear 215 35 meshing with a bevel gear 216, thus giving a driving connection to shaft 213. Normally, the tooth on the dog 209 (Fig. 1) is clear of the teeth in the ratchet wheel 208 but, when the shaft 213 is rotated the ratchet 208 will be lowered to engage the tooth in the dog 209 to stop the rotation of roller 200 which, however, will continue its downward movement until the soft rubber of which the roller is made is flattened against the stencil window. Attached to the central base 40 plate of the machine is a bracket 217 (Figs. 1 and 4) to which the guide plate 74, over which the envelopes are fed, is secured, said plate functioning as a platen to furnish a backing for both the envelope to be printed upon and the stencil which previously have been brought into printing relationship for the printing operation. The stencil card is fed above the guide plate 76 which has an opening in it registering with the window 44a of the stencil card to permit printing.

The rollers 202 and 203 are mounted in the side plates 190 and 191, similar to the mounting of the shaft 205 of the printing roller 200. The roller 202, however, is mounted on a shaft 220 which is slidably journaled in bushings 221 (Fig. 1) carried by side plates 190 and 191. The roller 200 is urged into contact with the roller 201 and the latter and roller 203 are urged into contact with the roller 202 by means of springs 225 and 226 (Figs. 2 and 4) which are engaged to spring hooks 227 and slides 228 shaped to wholly or partly surround the bushings of the support shafts of the respective rollers. The effect of these springs is to press the rollers 200, 201, 203 toward the shaft 220 and the springs 225 nearest the shaft 205 which are engaged to the spring hooks 227 and to slides 228 also hold the ball races of bearings 214 in engagement with cams 212.

The removable ink supply includes a framework consisting of side frames 230 (Figs. 1 and

11

4) joined together primarily by a casting 231. Plates 230 carry a rod 232 which rests in ears formed in the ends of a bracket 233 secured to the cross bar 194. The upper ends of the side plates 230 are provided with catches 234 (Fig. 4) pivoted by studs 235 which pass through slots in the catches. Catches 234 are hooked over the lower edge of the cross plate 193 and are actuated in a clockwise direction by springs 236 and due to the slots in the catches 234 springs 236 also tend to rock the frames 230 counterclockwise.

Between plates 230 and secured thereto by studs 237 (Fig. 4) are links 238 which rotatably mount the inking roller 204. The casting 231 secured between the plates 230 provides an ink reservoir 239 (Fig. 1) and has secured thereto a cover plate 240 and a doctor blade 241. A shaft 242 (Fig. 4) is rotatably supported in the plates 230 and extends to the right beyond the plate 191 and has a ratchet 243 which forms part of the means for rotating the shaft 242. Secured to the shaft 242 are a plurality of rollers or disks 244 (Fig. 1) which do not actually touch the roller 204. When shaft 202 is rotated, ink will be carried on the peripheries of the disks up to the roller 204. The spacing between the peripheries of the roller 204 and the rollers 244 is less than the thickness of the film of ink which the rollers 244 transport with the result that bands of ink are applied to the roller 204.

The doctor blade 241 is adjusted so as to not touch the rollers 244 and maintain the film of ink thereon of constant thickness and prevent over-charging roller 204 with ink.

Loosely mounted on the shaft 242 is an ink agitator 245 (Fig. 1) shaped somewhat like a ball which consists of a cylindrical plate, the inside surface of which is concentric with the rollers 244 but does not quite touch such rollers and which also clears the inside cylindrical surface of the ink reservoir 239. This agitator is formed with parallel slots extending longitudinally of the cylindrical plate and has an arm 246 cooperating with a cam 247 on the shaft on which roller 203 is mounted, whereby the agitator is given one oscillation for each complete revolution of the roller 203. Springs (not shown) are attached to the arm 246 to hold the arm in contact with the cam 247.

In order to spread the ink more evenly over the rollers the roller 202 (Fig. 2) is oscillated axially by a mechanism driven by the vertical drive shaft 112 (Figs. 1 and 3). For this purpose the drive shaft 112 carries a bevel gear 250 meshing with a bevel gear 251 secured to a shaft 253. Shaft 253 carries a bevel gear 254 in mesh with a bevel gear 255 carried by a shaft 256 which has secured to it a wide gear 257 (Fig. 5) meshing with a narrower gear 258 secured to the shaft 220 (Fig. 2) on which the roller 202 is mounted. The shaft 220 extends to the right and carries the aforementioned narrow gear 258 and also has freely mounted thereon a member 259 (Figs. 4 and 5) in the form of a casting having ears 260 (Fig. 5) receiving the shaft 220. Between the ears 260 is a worm 261 fixed to the extended portion of shaft 202. The casting member 259 is formed with an upward projection 262 (Fig. 4) which is freely slideable in a slot formed in a stationary guide plate 263 and also with a lower extension 264 slidably mounted in a fixed guide block 265. Thus, when the shaft 220 is oscillated axially the casting 259 may follow its movement but is prevented from

12

rotating about the axis of shaft 220, although such shaft can turn freely.

Pivoted on a stud 266 carried by the casting 259 is a worm wheel 267 which meshes with the worm wheel 261 and has a crank pin 268 connected by a link 269 (Fig. 2) to a pin carried by a fixed bracket 270 secured to the fixed side plate 18. It will be remembered that the shaft 220 turns continually in a print cycle, thus continually driving the inking rollers through the shaft 220. Also, when the shaft 220 rotates it drives the worm wheel 261 through the train of gearing described above, thereby alternately imparting thrust and tension to the link 269. This causes the casting 259 and hence the shaft 220 and roller 202 to move axially at a slow rate, thus spreading the ink evenly over the rollers 203, 201.

The ratchet wheel 243 is rotated by a mechanism shown in Figs. 4 and 5. The mechanism includes a slide 275 which is slotted to embrace the shaft 213 and a guide rod 276. A spring 277 anchored to a stud carried by the slide 275 urges the slide downwardly. The lower end of the slide carries a follower roller 279 which cooperates with a cam 278 on the shaft 213. Thus rotation of the shaft 213 causes a vertical reciprocatory movement of the slide 275 and at its upper end slide 275 carries a spring actuated pawl 280 engaging the ratchet wheel 243.

The guide rod 276 is provided with a cam 271 (Fig. 4) which is in the plane of a stud 272 carried by the operating slide 275 for the purpose of determining the starting position of the feeding pawl 280 and, therefore, the extent that it rotates the ratchet wheel 243. This covers the amount of ink fed in each operation. The rod 243 has secured to it a hand wheel 273 (Fig. 2) to position the cam 271 and said cam is held in the desired position by a detent 274 of the usual construction.

Card levers and card lever contacts

For the proper performance of the machine, especially in regard to selective operation of certain instrumentalities and the continuity of operation of the machine, the latter is provided with a number of card lever and associated contacts. The function of such contacts will appear in the drawings.

Mounted at the bottom of the card stencil supply hopper are the well known hopper contacts 281 (Fig. 2). The top portion of a pivoted lever 282 is pressed down by cards in the supply magazine to close the hopper contacts.

Also disposed in the envelope supply hopper (Fig. 1) is a similar card lever 283 which closes contacts 284 as long as there is a supply of envelopes in the hopper.

As cards emerge from the stencil card hopper and are fed by the first set of feeding rollers 75L (Fig. 2) they actuate a card lever 285 to close card lever contacts 286.

Associated with the envelope feeding rollers 170 (see Fig. 1) is a card lever 287 which is actuated by the envelope to close contacts 288. A supplemental card lever 289 is associated with the envelope discharge feeding rollers 171 and similarly closes the envelope position contacts 290. The latter contacts, as will subsequently appear in the wiring diagram, selectively control stencil printing operation.

Only a general description of the above card levers and associated contacts is given herein since they are well known.

Operation of machine in connection with circuit diagram

The operation of the machine will now be described in connection with the circuit diagram of Fig. 10 and timing diagram of Fig. 11.

Preliminary to an operation of the machine a switch S is closed to connect the power supply to power lines 299 and 301 and a crank lever 302 (Fig. 2) is rocked so that a cam 303 carried by the shaft of crank lever 302 closes contacts 304.

Incidentally the crank lever 302 is secured to a rock shaft 295 (Figs. 2 and 3) and the rock shaft has secured thereto an eccentric cam 291 (Fig. 3) which cooperates with a related depending link 292. Each link 292 is connected by a stud 294 to a plate 295 which is hooked over the extremities of the feed roller shafts which carry the upper rollers of the forward and rearward sets 170 and 171. By the rotation of the crank 302 the eccentric is positioned to elevate both links 292 and, therefore, raise the upper feeding rollers of the sets 170 and 171 to provide a separation with respect to the lower ones of said sets of rollers. This facilitates the removal of envelopes which may become jammed. However, when the crank lever 302 is in such position to close contacts 304 then the sets of feeding rollers 170 and 171 are in such position as to enable the feeding of the incoming and outgoing envelopes. Closure of contacts 304 closes an obvious circuit across the lines 299 and 301 to energize R1 relay. R1 relay closes R1a relay contacts to extend a line 300 to the power supply line 299. As long as envelopes are in the envelope supply hopper, the aforementioned contacts 284 are closed to energize the R5 relay by an obvious circuit. Also, as long as there are stencil cards in the stencil card receiving hopper, contacts 281 are closed to energize, by an obvious circuit, the R6 relay. The relays R5 and R6 close their respective contacts R5b and R6b which are in the pickup circuit of the pickup coil of the feed control relay R9.

Machines of this type are provided with cams which close and open contacts at different times in the cycle and cam operated contacts designated as CR1-CR7 (Fig. 11) are driven by the continuously rotating shaft 14 (Fig. 1). Additional cam contacts designated FR1 and FR2 in Fig. 11 are provided and are operable in a feed roll cycle. The cams for operating these contacts are driven by an extension of feed roller shaft 128 (see Fig. 6). PR1 contacts are controlled by a cam driven by shaft 253 (Fig. 3) which is operable during each printing cycle.

The depression of a Start Key so labeled in the circuit diagram will close contacts 305 to close a circuit to the R2 start relay when cam contacts CR2 close at 119°, the energizing circuit extending from line 300, CR2 cam contacts, the start key contacts 305, R2 start relay to line 301. For the sake of simplicity it will be assumed that the Start Key is held down until the first envelope is printed, machine operations thereafter being continuous. Closure of the R2a holding contacts extends a holding circuit back to line 300, through R2a contacts, CR1 cam contacts and stop key contacts 306. This holding circuit will extend the energization of the R2 relay over to 210° of the start cycle. At 160° of this start cycle, and before the aforementioned holding circuit is opened and R2 relay is deenergized, cam contacts CR4 will close to energize the R9 relay and the clutch control magnet 36 which initiate the feeding of envelopes by the following circuit:

From line 300, CR4 cam contacts, R4d relay contacts now closed, R2c relay contacts now closed, R5b relay contacts now transferred, R6b relay contacts now transferred, R3d relay contacts now closed, to the pickup winding of the R9 relay to line 301. A circuit also extends from R3d relay contacts, R1c relay contacts now transferred, to the envelope feed clutch control magnet 36 to line 301. The R9 relay is a duo-wound relay coil wherein P represents the pickup winding and H the holding winding. R9 relay, now being energized, closes the R9a holding contacts to energize the holding coil by a circuit extending from line through FR2 cam contacts now closed because its controlling cam is stationary at this time, through R9a relay contacts to the holding winding of the R9 relay to line 301 and such holding circuit is maintained closed until 20° of the second machine cycle which is a card and envelope feed roll cycle.

When the R9 relay is energized, it closes its R9b relay contacts, completing a circuit from line 300 through CR4 cam contacts, R4d relay contacts now closed, R9b relay contacts now closed to stencil card feed clutch control magnets 56 to line 301.

R9 relay closes R9c relay contacts so that when cam contacts CR6 close at 325° of the start cycle a circuit is closed from line 300, through CR6 cam contacts, R9c relay contacts to feed roll clutch control magnets 123 to line 301.

Energization of the envelope picker clutch magnets 36 effects a clutch connection at about 210° of the start cycle so that under control of the operating cam 34 the lowermost envelope is fed from its supply hopper to engage the first set of feeding rollers 170 (Fig. 1) at about 358° of the start cycle (see Fig. 11). Energization of the stencil card picker clutch control magnets 56 effects a clutch connection at about 252° of the start cycle so that under control of the operating cam 62 the lowermost stencil card is fed from the supply hopper to engage the first set of feeding rollers 75L (Fig. 2) at about 26° of the feed roll cycle.

Energization of the feed roll clutch magnets 123 by circuit connections just described causes a clutch connection at about 358° of the start cycle so that the rotation of feeding rollers 75L will feed the stencil card to printing position during the next cycle but not in such position that it is engaged by the second set of feeding rollers 75R. The stencil card is at printing position at about 358° of the feed roll cycle. Rotation of the first set of envelope feed rollers 170 will feed the envelope rearwardly to printing position so that the second set of feed rollers 171 receives this envelope while being fed to printing position. The envelope is at printing position at about 358° of the feed roll cycle. The third cycle is a print cycle and printing is effected from the first stencil card upon the first envelope fed.

The feeding of the first envelope causes the operation of card lever 287 to close contacts 288 at 346° of the start cycle. Further, the feeding of a stencil card in the start cycle causes the operation of a card lever 285 to close contacts 286 at 320° of the start cycle. By an obvious circuit relays R3 and R4 (Fig. 10) are energized and referring to Fig. 11 the continued closure of card lever contacts 288 and 285 will retain relays R3 and R4 energized to nearly the end of the feed roll cycle. However, a stick circuit maintains R3 and R4 relays energized

15

until 150° of the print cycle. The stick circuit for R3 relay extends back to line 300 through R3a relay contacts, R4d relay contacts, cam contacts CR3, whereas R4 relay is held energized through the R4a relay contacts and cam contacts CR3.

Even though the Start Key should be held depressed to pick up the R2 start relay and close contacts R2c in the pickup circuit of R9 relay, the latter and clutch control magnets 36 and 56 are not picked up in the print cycle because of the opening of contacts R4d and R3d. Since R9c contacts are now opened the feed roll clutch magnet 123 is not energized in a print cycle.

However, during the feed roll cycle the envelope position card lever 289 is operated to close contacts 290 at about 332° and also after this until 268° of the second feed roll cycle, so that when cam contacts FR1 close at 333° a circuit will be closed from line 300, through FR1 cam contacts, R3c relay contacts now closed, R4c relay contacts now closed, and card lever contacts 290 and print clutch control magnets 187 to line 301.

The energization of the clutch control magnets 187 will cause the engagement of a clutch at about 12° of the third or first print cycle so that under control of the pressure cams 212 printing from the stencil on the envelope will be effected during $96-192^\circ$ of the third cycle.

It should be noted that unless the start key is held down during the third cycle the stencil and card feed operations of the machine come to a stop after printing has been effected because cam contacts CR1 open at 210° of the first cycle (or the second cycle if the key is held depressed) to break the holding circuit of the R2 relay to deenergize the latter. A re-depression of the start key would be required in the third cycle, if the start key is not held down to again pick up the R2 relay to repeat operations in the fourth or second feed roll cycle which are the same as those effected during the first feed roll cycle, and previously described. At the end of the first print cycle clutch magnets 36 and 56 and feed roll clutch magnet 123 are again energized so that the envelope picker clutch and card picker clutch are again engaged so as to begin the feeding of the second stencil card and the second envelope from their respective hoppers in the manner previously described. The first envelope now having been printed under control of the first stencil card, circuits are rendered effective during the print cycle so that the stencil card is moved to the stacker and also the envelope is fed to its storage magazine. At the beginning of the start cycle the shuttle clutch control magnets 80 are normally energized to prevent the engagement of the shuttle clutch by a normally closed circuit extending from line 299, through R9d relay contacts now closed, shuttle clutch control magnets 80 to line 301. It will be recalled that R9 relay is energized at 160° to open contacts R9d but before this CR5 cam contacts close to retain clutch magnets 80 energized by an obvious circuit until 325° when such cam contacts open. This causes a clutch engagement at 350° and under control of the shuttle operating cam 81 the shuttle is operated but since the first stencil card is not in position to be fed by the shuttle this operation is an idle operation in the feed roll cycle. In the print cycle the operation is repeated as in the feed roll cycle and the shuttle clutch is engaged at 350° of the first print cycle. The

5

operation of the shuttle will move the first stencil card from printing position to a position where it is seized by the second set of feeding rollers 15R. The latter now being rotated will move the first stencil card to the storage hopper.

Since the feeding rollers 170, 171 of the envelope feeding mechanism are also rotating during the second feed roll cycle the printed envelope is fed to the storage hopper. A repetition of the events outlined in the timing diagram then ensues and stencil cards and envelopes are automatically fed and the envelopes printed without interruption.

It will be recalled that the holding circuit for the R2 relay is normally maintained by CR1 cam contacts until 210° of the machine cycle. However, a supplemental holding circuit is provided by relay contacts R4b and R3b for a portion of the cycle by a holding circuit extending through R2a relay contacts, R3b relay contacts, R4b relay contacts, R5a relay contacts, R6a relay contacts, stop key contacts 306 to line 300. This holding circuit is broken when R3b and R4b relay contacts open at 150° of each print cycle when CR3 cam contacts open. However, during this cycle the R2 relay is maintained energized after 150° of the print cycle by cam contacts PR1 and these contacts keep the R2 relay energized to the end of the print cycle to open at 10° of the following, or second feed roll cycle. During the above mentioned feed roll cycle, if both a new stencil card and a new envelope have been fed, the holding circuit for the R2 relay will now again be maintained through the R3b and R4b contacts. Thus, as long as cards and envelopes feed, relay R2 will be held energized through either the card and envelope card lever relay circuits or the PR1 cam contact.

Hence, the machine will continue running as long as none of the following conditions occurs.

- 40 1. Either hopper runs out of cards or envelopes.
2. Either a card or an envelope fails to feed.
3. Either a card or an envelope fails to be moved properly to printing position.
- 45 4. Stop key is depressed.

50 1. In this case the machine will stop because either the R5 or R6 relay will be deenergized so as to open contacts R6a and R5a in the machine running circuit. In this case the hopper which is empty must be refilled and the Start Key depressed or cards or envelopes removed from the hopper which was not empty and the Start Key depressed.

55 2. In this case when either a card or envelope fails to feed the machine can be started by depression of the Start Key as soon as reason for failure to feed has been corrected. However, there will be an unprinted card or envelope, depending upon which item is fed.

60 3. When either a card or envelope fails to feed clear into printing position the Runout Key, so labeled in the wiring diagram, will be operated. When this condition occurs either one or the other of the R3 or R4 relays will be deenergized and their b contacts will be open to break the supplemental holding circuit of the R2 relay. The 2c relay contacts will be opened to prevent the pickup of the R9 relay. Depression of the Runout Key will cause both the envelope and stencil card to be run out of the machine without having been printed and to restore the machine to normal, cam contacts CR1 are so timed that depression of the Runout Key results in the energization of feed roll clutch magnet 123 and 75 shuttle clutch magnet 80 but does not permit

16

either the stencil card or envelope picker clutch to operate.

The circuit for energizing the R9 relay by means of the Runout Key is as follows: From the line 300 through the FR2 cam contacts, the Runout Key contacts 315, cam contacts CR1, the R2b relay contacts now closed, the R9 holding coil, to line 300. Closure of the R9c contacts enables the feed roll clutch magnet 123 to be picked up under control of cam contacts CR6 and the opening of the R9d relay contacts enables shuttle clutch magnet 80 to be deenergized when cam contacts CR5 open. It will be recalled that the clutch action controlled by this clutch magnet is effective when the magnet is deenergized.

4. The depression of the stop key opens the stop key contacts 306 and all that is necessary is a momentary depression at any time to inhibit further stencil card and envelope feeding operations.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In an address printing machine operable in successive cycles wherein one cycle comprises a feed roll cycle and the following cycle a printing cycle, the combination of means for feeding record materials to be printed separately from a supply hopper to printing position, means for sensing said record material to determine whether it has been fed to and is at printing position, means for feeding printing plates separately from another supply hopper to printing position and in a printing relationship with respect to said record materials, means tending to effect the operation of both of said feeding means in said feed roll cycle and said printing cycle, means for detecting whether a printing plate and record material has been fed out of the related hopper towards printing position, means controlled by said detecting means for preventing the means which effects the operation of said feeding means from being effective to cause the operation of said feeding means during the following printing cycle, means to effect printing from a printing plate on the record material in printing position, and means controlled by the aforesaid sensing and detecting means and operable by an element operable in a feed roll cycle to cause the operation of said printing means in said following printing cycle when both of said feeding means are idle and upon said sensing means sensing that a record material is at printing position and said detecting means has detected that both a record material and printing plate have been fed out of their respective hoppers and are at printing position.

2. In an address printing machine operable in successive cycles wherein one cycle comprises a feed roll cycle and the following cycle a printing cycle, the combination of means for feeding record materials to be printed separately from a supply hopper to printing position, said means including a pair of feeding rolls and a pair of discharge rolls, means for sensing said record material to determine whether it has been fed to and

is at printing position, means for feeding printing plates separately from another supply hopper to printing position and in a printing relationship with respect to said record materials, said means including a pair of feeding rolls and a pair of discharge rolls, means tending to effect the operation of both of said feeding means including all of said feed and discharge rolls in said feed roll cycle and said printing cycle, means for detecting whether a printing plate and record material has been fed out of the related hopper towards printing position, means controlled by said detecting means for preventing the means which effects the operation of both of said feeding means and all of said feed rolls and discharge rolls from being effective to cause the operation of said feeding means and said feed and discharge rolls during the following printing cycle, means to effect printing from a printing plate on the record material in printing position, and means controlled by the aforesaid sensing and detecting means and operable by an element operable in a feed roll cycle to cause the operation of said printing means in said following printing cycle when both of said feeding means are idle upon said sensing means sensing that a record material is at printing position and said detecting means has detected that both a record material and printing plate have been fed out of their respective hoppers and are at printing position, said means which effects the operation of both of said feeding means and feed rolls causing the feeding of a following printing plate and record material to printing position, and said discharge rolls to discharge the printed record material and associated printing plate to discharge position.

3. In a machine for printing upon separate record materials from printing plates wherein said printing plates and record materials are fed in a feed roll cycle, and printing is effected in a subsequent printing cycle, a main operating means for said machine, means for feeding printing plates from a hopper to printing position, means for feeding said record materials from a hopper to printing position, each of said means including a clutch connected to said main operating means, and operable during a feed roll cycle, means for sensing said printing plates and record materials to determine whether a printing plate has been fed out of the related hopper and whether a record material has been fed out of the related hopper, means tending to connect said clutches to said main operating means in each feed roll and print machine cycle, means controlled by said sensing means upon sensing that a printing plate and record material have not been fed out of their respective hoppers for preventing the preceding means from being effective in a subsequent or print cycle, and means operable in said printing cycle to effect printing from a printing plate on a record material which is in printing position.

4. In a machine for printing upon separate record materials from printing plates wherein said printing plates and record materials are fed in a feed roll cycle, and printing is effected in a subsequent printing cycle, a main operating means for said machine, means for feeding printing plates from a hopper to printing position, means for feeding said record materials from a hopper to printing position, each of said means including a clutch connected to said main operating means and operable in a feed roll cycle, means for detecting whether record materials are

in the related supply hopper and whether printing plates are in the related supply hopper, means for sensing said printing plates and record materials to determine whether a printing plate has been fed out of the related hopper and whether a record material has been fed out of the related hopper, means tending to connect said clutches to said main operating means in each machine cycle, means under control of said detecting means to enable said clutch connection when both record materials and printing plates are in the hoppers, means controlled by said sensing means upon sensing that a printing plate and record material have not been fed out of their respective hoppers for preventing the means which connects the clutches to said main operating means from being effective in a subsequent or print cycle, and means operable in a printing cycle to effect printing from a printing plate on a record material which is in printing position.

5. In a machine for printing upon separate record materials from printing plates wherein said printing plates and record materials are fed in a feed roll cycle, and printing is effected in a subsequent printing cycle, a main operating means for said machine, means for feeding printing plates from a hopper to printing position, means for feeding said record materials from a hopper to printing position, each of said means including a clutch connected to said main operating means and operable in a feed roll cycle, means for sensing said printing plates and record materials to determine whether a printing plate has been fed out of the related hopper and whether a record material has been fed out of the related hopper, means operable in a printing cycle to effect printing from a printing plate on a record material when both are in printing position and including a clutch connected to said main operating means, means tending to connect the clutches for both feeding means to said main operating means in each print cycle and feed roll machine cycle, means controlled by said sensing means upon sensing that a printing plate and record material have not been fed out of their respective hoppers for preventing the preceding means from being effective in a subsequent or print cycle, and means controlled by said sensing means for preventing the operation of the printing means upon failure to feed either a printing plate or record material to printing position.

6. In a machine for printing upon separate record materials from printing plates wherein

said printing plates and record materials are fed in a feed roll cycle, and printing is effected in a subsequent printing cycle, a main operating means for said machine, means for feeding printing plates from a hopper to printing position, means for feeding said record materials from a hopper to printing position, each of said means including a clutch connected to said main operating means, means for detecting whether record materials are in the related supply hopper and whether printing plates are in the related supply hopper, means for sensing said printing plates and record materials to determine whether a printing plate has been fed out of the related hopper and whether a record material has been fed out of the related hopper, means tending to connect said clutches to said main operating means in each print and feed roll machine cycle, means under control of said detecting means to enable said connection when both record materials and printing plates are in the hoppers, means controlled by said sensing means upon sensing that a printing plate and record material have not been fed out of their respective hoppers for preventing the means which connects the clutches to the main operating means from being effective in a subsequent or print cycle, means operable in a print cycle to effect printing from a printing plate on a record material which is in printing position, and means controlled by said sensing means to prevent the operation of the printing means upon failure to feed either a printing plate or record material to printing position.
